US00D851663S

(12) **United States Design Patent** (10) **Patent No.:** **US D851,663 S**
Guesnon, Jr. (45) **Date of Patent:** **** Jun. 18, 2019**

(54) **DISPLAY SCREEN OR PORTION THEREOF WITH GRAPHICAL USER INTERFACE**

(71) Applicant: **Thales Avionics, Inc.**, Irvine, CA (US)

(72) Inventor: **Andrew A. Guesnon, Jr.**, Anaheim Hills, CA (US)

(73) Assignee: **Thales Avionics, Inc.**, Irvine, CA (US)

(***) Term: **15 Years**

(21) Appl. No.: **29/585,163**

(22) Filed: **Nov. 21, 2016**

Related U.S. Application Data

(63) Continuation of application No. 29/451,663, filed on Apr. 5, 2013, now abandoned.

(51) **LOC (11) Cl.** **14-04**

(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing the design;

FIG. 2 is a front view of a second embodiment of a display screen or portion thereof with graphical user interface showing the design; and,

FIG. 3 is a front view of a third embodiment of a display screen or portion thereof with graphical user interface showing the design.

The broken lines shown in FIGS. 1-3 represent portions of the display screen or portion thereof with graphical user interface that form no part of the claimed design.

1 Claim, 3 Drawing Sheets
